UNITED STATES PATENT OFFICE

162,007

MOLDED FIBER SERVICE PLATE

Charles J. Chaplin, South Portland, Maine, assignor to Chaplin Corporation, South Portland, Maine, a corporation of Maine

Application July 26, 1949, Serial No. 4,136

Term of patent 14 years

(Cl. D44—15)

To all whom it may concern:

Be it known that I, Charles J. Chaplin, a citizen of the United States of America, residing at South Portland, in the county of Cumberland and State of Maine, have invented a new, original, and ornamental Design for a Molded Fiber Service Plate, of which the following is a specification, reference being had to the accompanying drawing forming part thereof.

In the drawing:

Fig. 1 is a bottom plan view of a molded fiber service plate, showing my new design.

Fig. 2 is a side elevational view of the plate of Fig. 1, partly in elevation and partly in central section.

Fig. 3 is an enlarged fragmentary sectional view thereof.

The upper or inner surface of the plate is smooth and plain.

I claim:

The ornamental design for a molded fiber service plate, as shown and described.

CHARLES J. CHAPLIN.
